ABSTRACT

There is provided amusement apparatus enabling an externally rearwardly positioned operator to peer forwardly into an upright hollow housing and containing therewithin at least one target that is scoreably negotiable by the operator with a manipulatable weapon attached to the housing. The housed target is also independently scoreably negotiable by a programmed visible robot which seemingly to the operator takes aim and actively competes with him for the same target. Preferred embodiments include a plurality of distinct target locations, scheduling for automatically briefly displaying individual targets according to a predetermined schedule whereby the operator and robot might simultaneously compete for being the first to score a same target, an indicator to indicate the relative success of the operator and the robot of negotiating the target, reversing apparatus for the robot program relative to the targets presentation schedule thereby frustrating the operator's attempt to anticipate the robot, and handicaps to sharpen the robot and operator competition according to the operator's demonstrated weapon skill.

SHOOTING GALLERY APPARATUS IN WHICH A PROGRAMMED ROBOT COMPETES WITH THE OPERATOR

This invention relates to certain noteworthy improvements for amusement apparatus of the so-called "shooting galleries" type wherein the operator aims a rifle or other manipulatable weapon (real or simulated) toward forwardly remote targets. "Shooting gallery" type amusement apparatus of more recent years are of a relatively compact portable nature and commonly comprise a housing containing therewithin one or more targets and a forwardly pointing manually aimable and actuatable weapon attached to the housing. Thus, a rearwardly positioned operator might scoreably negotiate the targets through forwardly propelled missiles, through electrical circuit connections, etc. Over the years there has been the continued quest to make "shooting galleries" more interesting and challenging to the weapon-wielding operator. In this regard, attention has been directed largely to the targets, such as making the targets rapidly moving or of briefly scheduled appearance to make them more difficult for the operator to scoreably negotiate. However, target intricacies and scheduling are quickly mastered by more sophisticated operators and such players soon become disinterested.

More recent prior art workers have concluded that interest and challenge are best provided in "shooting gallery" type apparatus when a competition element is introduced thereto. In this vein, two or more weapons have been provided for use by a number of operators who can then compare their relative success in scoreably negotiating the same targets. However, such plural-operators apparatus are not appropriate to companions of widely disparate weapon skill nor to the unaccompanied individual who wishes to participate by himself. To accommodate the solo operator, so-called "dueling apparatus," such as in U.S. Pat. Nos. 2,404,653 (Plebanek) and 2,957,693 (Ross), have been developed wherein a mechanical manikin and the operator aim at each other in dueling fashion. However in such dueling apparatus the manikin opponent has tended to have slow and simple motions, which offers insufficient challenge to most players.

It is accordingly the general object of the present invention to provide a "shooting gallery" type amusement apparatus having the element of competition and that offers an unusually high degree of interest and challenge to operators of various degrees of weaponry skill, including highly skilled and sophisticated operators.

It is another general object to provide a "shooting gallery" type competition amusement apparatus wherein the competitor is a robot adapted to actively aim toward and compete for the same targets as does the operator.

It is a further and ancillary object to provide an amusement apparatus of the target shooting type wherein pre-scheduled targets are automatically briefly displayed for simultaneous availability either to the robot or to the operator.

It is another object to provide a robot competitor target shooting type apparatus wherein there are means to frustrate the operator's attempt to anticipate the robot's targeting maneuvers.

It is a further object to "humanize" the robot competitor to the extent that it sometimes apparently fails

attempts to scoreably negotiate targets, yet that offers challenging competition to relatively skilled operators.

With the above and other objects and advantages in view, which will become more apparent as this description proceeds, the amusement apparatus of the shooting gallery type generally comprises a housing with a light-transmissive rearward side and including an externally rearwardly located operator's station, target means located within the housing and capable of being scoreably negotiated independently by an operator's weapon manipulatable at the operator's station and also by a robot competitive-armament attached to the housing and visually prominent from the operator's station, program means for automatically controlling the time period for the robot to scoreably negotiate the target means, indicator means to indicate the relative success of the operator's weapon and the robot competitive-armament to scoreably negotiate the same target, and other means for enhancing realistic and interesting competition between the operator and robot for a displayed target.

In the drawing, wherein like characters refer to like parts in the several views, and in which:

FIG. 1 is a perspective view of a representative form of the shooting gallery type amusement apparatus of the present invention, rearward and lateral portions of a hollow housing frame being broken away to show certain internal constructional details.

FIG. 2 is a sectional plan view taken along longitudinally extending horizontal line 2-2 of FIG. 1.

FIG. 3 is a sectional plan view taken along lines 3-3 of FIGS. 1 and 2.

FIG. 4 is a schematic circuit diagram for the target shooting apparatus embodiment of FIGS. 1-3.

An initial brief treatment of the comparatively simplified FIGS. 1 and 2 will serve to explain relative to embodiment "S" certain noteworthy features of the target shooting type amusement apparatus of the present invention. Apparatus S generally comprises: an upright hollow housing 10 including an upright rearward portion including a light-transmissive opening 11D whereby a player located at a rearward operator's station (e.g. standing alongside 11F) might view forwardly into the housing interior. There are target means displayable at ready-condition within the housing from a plurality of distinct locations; herein there are three separated "pop-up" targets "TA," "TB," "TC," each being automatically briefly displayable at "up" ready-condition. At the time instant of FIGS. 1-4, "pop-up" target "TB" only is in the "up" ready-condition while the similarly actuatable targets "TA" and "TC" are "down" beneath opaque screen 17 and temporarily out-of-play. There is a simulated operator's weapon, such as the shoulder-gun form 40, located at the operator's station; the player's weapon "40" is manually aimable toward and capable of scoreably negotiating the target means. A robot 50 (herein comprising a humanized toy figurine 50M and including the appearance of a waring implement, e.g. elongated rifle form 51), is automatically programmed for scoreably negotiating the target means and offering to the operator the visual phenomenon of competitive-armament (e.g. 51) capable of independently actively competing with the operator's weapon for the same target. For example, during the time when center target "TB" only is displayed at ready-condition, it can be scoreably negotiated independently by the player's weapon 40 or by the robot

50

55

60

65

whichever first aims accurately theretoward, as indicated in solid lines 40B and 51B. However, as indicated by phantom lines 40A and 51A and also by phantom line 40C and 51C, the operator's weapon and the robot can each independently scoreably negotiate other targets (e.g. "TA" and "TC," respectively) whenever they are displayed at ready-condition. The indicator means (such as through sound indicator, light indicator, scoreboard 100 and timer 101, etc.) can then indicate how well the player fares compared to the robot competitor relative to the same target. As will be pointed out later in greater detail, it is desireable for the purposes of enhancing realistic competition to have means for removing a ready-condition target from display immediately upon its initial scoreably negotiated "hit," whether by the operator (40) or by the competitive-armament (51).

Commencing now the detailed description, the preferred upright hollow housing 10 comprises a plurality of interconnected panels 11 - 16, herein as a pair of horizontal rectangular planar panels including a roof-panel loftily overlying a floor-panel 16, a vertical rectangular planar front-panel 12, a pair of planar vertical (herein seven-sided) lateral-panels including left-panel 13 and right-panel 14, and a generally vertically extending rearward side 11. A plurality of legs 19, herein four in number, depend from the respective corners of floor-panel 16 to elevate the relatively stationary housing 10 above an underlying substrate (not shown). A scoreboard 100 and time-clock 101 might be supported upon housing roof-panel 15. Rear-panel 11 comprises four rectangular planar sections including the vertical light-transmissive upper-section 11D, a dashboard second-section 11E extending horizontally rearwardly of the upper-section lower end, a third section 11F extending vertically downwardly of the second-section rearward terminus, and a fourth-section 11G extending obliquely downwardly-forwardly from the lower end of the third-section 11F to the rearward end of floor-panel 16. The dashboard 11E (to which weapon "W" is attached) and the third-section 11F (against which the player might lean) together provide the rearwardly located operator's station. There is herein an upright brace-panel 11H located immediately forwardly of panels 11F and 11G and extending vertically upwardly from the rearward end of floor-panel 16 to be co-planar with transparent panel 11D. Commencing at brace-panel 11H (at co-elevation with dashboard 11E) and extending upwardly and forwardly therefrom to front-panel 12 is an opaque screen 17. Screen 17 is provided with three keyhole openings 17A, 17B, and 17C to allow respective targets "TA," "TB," and "TC" to briefly "pop-up" into view from beneath screen 17. A base-panel 18 located beneath screen 17 extends between panels 11H and 12.

Each of the three briefly displayable "pop-up" targets "T" is identical, and accordingly, the same reference characters might be used relative to the constructional details of target members "Ta," "TB," and "TC." Each target "T" comprises a circular marker 21, at which the operator takes aim for scoring; marker 21 is attached to the upper end of an angular standard 22. An electromagnetic solenoid 25 having a horizontally reciprocatable spring-loaded normally-extended armature 26 causes the "popping-up" of marker 21, solenoid 25 being attached to base-panel 18. In this vein, the lower end of standard 22 lies alongside the arma-

ture 26 and is pivotably attached thereto with pin 23. A medial portion of standard 22 lies alongside a bracket 27 carried by the solenoid housing and is pivotably attached thereto with pin 24. Thus, as indicated with solid line in target "TB" and with phantom line in target "TC," during the time period when solenoid 25 is electrically actuated the armature 26 moves horizontally toward the solenoid housing and the target marker 21 is in the "up" ready-condition, and above screen 17. However, as indicated with phantom line in target "TB" and with solid line in target "TC," whenever there is an absence of electrical current flow to the solenoid, the spring-loaded armature 26 is extended further away from the solenoid housing; thus, the marker 21 is not in ready-condition, but is rather "down" into the screen openings, e.g. 17C.

As is well known in the prior art, the targets "T" might be briefly displayed in "up" ready-condition, according to a prescribed automatic schedule. For example, such target scheduling means might be based upon a so-called "stepper unit." Target stepper 30 herein comprises an electrically non-conductive rectangular planar matrix 31 rigidly attached to housing front-panel 12. Rotatably associated with and extending through the geometric center of matrix 31 is a rod 32. Parallel to one side of matrix 31 and extending radially from 32 is an electrically-conductive wiper-arm 33, and parallel to the other side of matrix 31 is a ratchet-wheel 34, elements 33 and 34 being corotatably attached to rod 32. Matrix 31 has a plurality of isolated electrically-conductive contact-stations (herein eight isolated buttons spaced at regular 45° increments about center 32) which are adapted to be contacted step-wise by wiper-arm 33. Thus, assuming a suitable initiator (such as pawl 35 and eight-teeth ratchet-wheel 34) causes rod 32 to rotate step-wise at appropriate angular increments, electrical energy is capable of being passed from rod 32 via stepwise wiper-arm 33 and the matrix buttons to an external load, e.g. the respective solenoids 25, matrices 49 and 56, etc. As will be reiterated later, for units 81 and 87, elements analogous to 31 (with incremental contact-stations), 32, 33, and an initiator (e.g. 34-35) are common to "stepper units" generally. For target stepper 30 three of the eight distinct button contact-stations are arbitrarily called "C" because each is electrically connected to the solenoid 25C for target "TC." Similarly, another three of the stepper 30 buttons are arbitrarily called "B" because each is electrically connected to the solenoid 25B for target "TB;" the remaining two buttons are arbitrarily called "A," each being electrically connected to the solenoid 25A for target "TA." Thus, the angular position of the wiper-arm 33 determines which target "T" is at "up" ready-condition; in the drawing wiper-arm 33 is arbitrarily shown at a button "B" and target "TB" through solenoid 25B is at ready-condition. As indicated schematically in FIG. 3, the initiator 34 is driven at small angular increments in conventional fashion with a pawl 35 reciprocatably motivated by stepper-solenoid 37 via pivot-link 36.

The operator's simulated weapon, e.g. 40, is capable of apparently scoreably negotiating the ready-condition targets according to various principles of the prior art. For example, simulated shoulder-gun 40 includes a stick 41 extending rigidly downwardly therefrom through an enlarged opening of dash-board 11E, and an apertured ball 42 has a fixed location along stick

41. Extending above dash-board 11E is a socket 43 for seating ball 42; thus, shoulder-gun 40 is supported at universal joint 42-43 and is manually aimable in both azimuth and elevation toward the individual targets "T." An arm 45 is pivotably attached to the lower end of stick 41 with pivot-pin 44 and extends downwardly-forwardly therefrom toward a stationary electrically-insulative horizontal matrix 49 located below dash-board 11E and attached to panel 11F. An electrically-conductive springy leaf 46 (having rearward ear 47) extends downwardly-forwardly from arm 45 and is adapted to bear against the electrically-conductive contact-station buttons 49A, 49B, and 49C which extend upwardly from matrix 49. The isolated positions of buttons 49A, 49B, and 49C on matrix 49 are empirically selected according to the resultant position of leaf 46 when weapon 40 is aimably aligned with the respective ready-condition targets "TA," "TB," and "TC." Thus, a ready-condition target "T" might be scoreably negotiated or "hit" whenever the operator takes correct aim with weapon 40, which "hit" can be recorded onto scoreboard 100 or some other indicator means. In this vein, electrical wiring might extend from leaf ear 47 to first inductive coil 90 capable of actuating a relay pole 91 for scoreboard 100. Weapon 40 might optionally include a manipulatable trigger-switch 48 interposed between coil 90 and leaf ear 47.

As is well known in the prior art, for targets briefly displayable at ready-condition, it is desireable that a "hit" target be immediately withdrawn from view and a subsequent ready-condition target be immediately displayed. In the case of a plurality of "pop-up" targets "T," there is herein independent wiring between button 49A and the target "TA" solenoid 25A; between button 49B and the target "TB" solenoid 25B; and between button 49C and the target "TC" solenoid 25C. First conductive coil 90 is capable of actuating a relay pole 92 to de-energize the solenoid 25 for that ready-condition target which has just been scoreably negotiated by weapon 40 whereupon current is permitted to pass to stepper-solenoid 37 and stepper unit 30 causes the next scheduled target to be displayed at ready-condition. At the instant shown in the drawing, target "TB" is at ready-condition and leaf 46 is approaching button 49B from the counterclockwise direction as indicated by the double-headed curved arrow. When weapon 40 is correctly aimed at target "TB" and leaf 46 contacts button 49B (and optional trigger 48 actuated), solenoid 37 causes wiper-arm 33 to advance to button "A" and concurrently marker 21 of target "TA" moves above screen 17 and to ready-condition and target "TB" drops therebelow.

As a marked departure from the prior art, there is attached to the housing automatically programmed competitive-armament apparently capable of independently scoreably negotiating the target means thereby offering a simulated competitor for the operator's weapon. In other words, there is offered to the rearwardly stationed operator the visual phenomenon of competitive-armament (e.g. simulated waring implement 51) actively competing with the operator's weapon (e.g. 40) for the same target. Preferably, the competitive-armament is located within housing 10 and clearly seen to the operator, such as being positioned at 50 between panels 12 and 11D and above opaque screen 17. For the purposes of providing a realistic type competitor to the operator, the robot competitive-

armament (e.g. elongate simulated waring rifle 51) is movable directionally by the robot's automatic programmed control means so as to be necessarily extended toward the ready-condition target before same 5 can be scoreably negotiated, i.e. "hit."

For the robot embodiment 50 shown in the drawing, there is an uprightly extending figurine (e.g. humanized manikin 50M) which integrally includes therewith an elongated horizontal waring rifle form 51 as the simulated competitive-armament. Rigidly attached to the manikin 50M and extending vertically downwardly therefrom through an enlarged opening of screen 17 is the vertical shaft 59 of motor 58. Motor 58, which is preferably of the type having selectable dual-directional capability for its shaft 59 (as through two motor coils 58J and 58K), is herein attached to base-panel 18 immediately forwardly of brace-panel 11H. Rotatable motor shaft 59 also extends through an enlarged opening of a horizontal matrix 56 (analogous to elements 31 and 49) which is herein stationarily attached to the upper portion of brace-panel 11H. An electrically-conductive sweeper-bar 52 (having rear end 52R) extends horizontally forwardly from rotatable motor shaft 59 and in vertical alignment with co-rotatable rifle form 51. Sweeper-bar 52 is adapted to contact electrically-conductive contact-station buttons 56A, 56B, and 56C which extend upwardly at isolated locations from matrix 56. Analogous as for buttons 49A-49C, the positions of isolated buttons 56A, 56B, and 56C on matrix 56 are empirically selected according to the resultant position of sweeper-bar 52 when the robot's simulated competitive-armament 51 is nominally aimably aligned with the respective ready-condition targets "TA," "TB," and "TC." Thus, as exemplified in FIG. 4, if each button contact-station of matrix 56 is independently wired or otherwise actuatable connected to a single target "T," then the automatically programmed robot 50 is capable of itself scoreably negotiating a target "T," thereby providing simulated competition for the player's weaponry skill. For example, at the time instant alluded to in FIGS. 3 and 4, motor 58 is causing co-rotatable elements 51 and 52 to move counterclockwise (tri-headed curved arrow) toward button station 56B. If this happens before the operator can maneuver weapon 40 to attain contact between leaf spring 46 and button 49B, then target "TB" is scoreably negotiated or "hit" first (and "won") by the robot 50.

As is best seen in FIG. 4, if each button station of matrix 50 is independently wired (or otherwise actuatable connected) to only a single target "T," then the target scoring of the robot can be exhibited in some fashion. For example, the above described "pop-up" type briefly displayable targets might be capable of being withdrawn from view immediately upon being first "hit," whether attained first by the player or by the robot. In this regard, as seen in FIG. 4, each button station of matrix 56 is independently wired to a solenoid 25 of a different target "T," and in parallelism to the independent wiring from the buttons of matrix 49 to said individual solenoids 25. Further, electrical wiring might extend from the sweeper-bar rear end 52R to a second inductive coil 95. Coil 95 is capable of actuating a relay pole 96 (in circuit parallelism with relay pole 92) to deenergize the solenoid 25 of the "hit" target whereupon stepper-solenoid 37 is actuated and the next scheduled ready-condition target appears. As indi-

cated in FIG. 4, after the ready-condition target "TB" is first scoreably negotiated, either by the player's weapon 40 or by the robot (51), the target scheduling means via stepper-solenoid 37 and clockwise moving wiper-arm 33 causes target "TA" to appear next in ready-condition. As seen from the arbitrarily selected buttons order on matrix 31, next subsequent targets singly displayed are: "TC," "TB," "TC," etc.

As had been previously alluded to, there are indicator means to indicate the relative success of the operator's weapon (40) and the automatically programmed competitive-armament (51) to scoreably negotiate the target means. For example, different audio indicators might be used, e.g. a bell rung if the player wins a target and a horn sounded if the robot wins that same target. Or, there might be two scoreboards, one to record the number of "hits" made by the player and another to record the number of targets "hit" by the robot. Herein, the indicator means arbitrarily shown includes a game timer 101 during which time some number of singly displayed ready-condition targets are available to both the robot and to the player; the number of targets won by the player (e.g. 06) is recorded on scoreboard 100. Herein, timer 101 is shown interposed in the circuitry adjacent to power supply 110.

There are desireably handicap means to adapt the apparatus to operators of widely differing weaponry skills. For the purpose of aiding the novice or relatively unskilled players, an intermittent interrupter means might be introduced into the robot program whereby the robot's target scoring capability is reduced. For example, a pair of normally-separated springy contacts 67 and 68 might be interposed in the circuitry between second inductive coil 95 and the sweeper-arm 52. A cam 69 rotating at some constant speed (e.g. the angular velocity for motor shaft 59) and according to some arbitrarily selected cam contour, is able to press contact 68 against contact 67 on an intermittent basis. For example, with that cam contour arbitrarily selected for FIG. 4, the robot 50 is able to scoreably negotiate a ready-condition target "T" only intermittently and during about 50 percent of the overall playing time 101.

On the other hand, for the purpose of making the robot competition shooting type game more challenging for higher skilled players, the time required for the robot to scoreably negotiate the ready-condition targets can be reduced. For example, the angular velocity of motor shaft 59 might be automatically increased when the player himself has won a predetermined number of targets. In this vein, there might be a pair of parallel electrical resistors 88 and 89 interposed between the power supply 97 and motor 58, the higher value resistor 89 only influencing the motor 58 during the game initial duration whereby the speed of shaft 59 and robot 50 is relatively slow. However, for the parallel branch of the lower value resistor 88 there is a stepper unit 87 (similar in construction to stepper 30) to isolate said low value resistor 88 during the early duration of play and until the player makes a prescribed number of target "hits." The stepper 87 is arbitrarily designed to bring and to maintain low resistor 88 into the circuitry of motor 58 when the operator makes ten "winning hits." In this vein, coil 90 is also capable of actuating relay pole 93 which controls through solenoid 85 the first ten steps of stepper 87.

Oftentimes the more experienced operator will be able to memorize the target scheduling means, e.g. 30,

and in this way gains undue advantage in being able to anticipate the robot's program for approaching the next scheduled target. In order to neutralize those anticipatory maneuvers by the player, there can be means to automatically reverse the angular direction of robot 50 and shaft 59 each time the robot wins a target from the player, or the operator wins a target from the robot, or other selected stimulus stemming from the relative success between the competitors. For the arbitrarily selected stimulus herein, motor shaft 59 reverses direction each time the robot wins a target. As has been previously alluded to, motor 58 might be of the dual-directional type which has two sets of windings (e.g. 58J and 58K). Selective current flow to one of the two motor windings sets is governed by the stepper unit 81. In this vein, coil 95 is also capable of actuating relay pole 97 which controls through solenoid 82 the stepper 81 which is structurally analogous to steppers 30 and 87.

10 From the foregoing, the construction and operation of the robot competition shooting gallery amusement apparatus will be readily understood and further explanation is believed to be unnecessary. However, since numerous modifications and changes will readily occur to those skilled in the art, it is not desired to limit the invention to the exact construction shown and described, and accordingly, all suitable modifications and equivalents may be resorted to, falling within the scope of the appended claims.

I claim:

1. Amusement apparatus of the shooting gallery type and comprising:

- A. An upright hollow housing with a light-transmissive rearward side and also including a rearwardly located operator's station;
- B. Target means comprising at least one target located within said housing forwardly of the operator's station,
- C. an operator manipulatable weapon located rearwardly of the target means, said target means being capable of being scoreably negotiated by said weapon;
- D. robot means including a robot within said housing and being capable of scoreably negotiating the target independently of the operator, said robot offering to the stationed operator the visual phenomenon of competitive-armament capable of competing with the operator's weapon for scoreably negotiating said target means;
- E. Program means for automatically controlling the time required for the robot competitive-armament to scoreably negotiate said target means; and
- F. Indicator means to indicate the relative success of the operator manipulated weapon and the automatically programmed robot to scoreably negotiate the target means.

2. The shooting gallery type amusement apparatus of claim 1 wherein the robot comprises a figurine located within the housing and visually prominent to the operator, the figurine further having attached thereto a simulated waring implement extendable directionally toward the target means.

3. The amusement apparatus of claim 2 wherein the target means is displayable at scoreably negotiable ready-condition from a plurality of distinct locations within said housing; and wherein the robot programming means is capable of extending the waring imple-

ment and in scoring capability toward a plurality of said distinct target locations.

4. The amusement apparatus of claim 3 wherein the target means includes a plurality of targets, individual targets being briefly automatically displayed to the operator at ready-condition according to a prescribed target scheduling means; wherein the robot waring implement is rotatably associated with respect to said housing, the robot programming means actuatable extending from the rotatable waring implement to the indicator means; and wherein for an individual target member at ready-condition and upon its initial scoreable negotiation by the competing operator's weapon and the programmed competitive-armament there are means for automatically removing said target from ready-condition display.

5. The amusement apparatus of claim 4 wherein the scheduling means for the targets comprises a stepper unit that is advanced step-wise upon the initial scoreable negotiation of a target; and wherein the robot includes a sweeper-bar in substantial vertical alignment and co-rotatable with the waring implement, said sweeper-bar being adapted to be in electrical conductive relationship with contact-stations nominally coinciding with the angular positions of said distinct target locations.

6. The amusement apparatus of claim 5 wherein the corotatable sweeper-bar and waring implement reverse direction whenever the robot competitive-armament wins a target thereby providing robot program reversing means relative to the targets scheduling means so as to frustrate the operator's attempt to anticipate the robot; and wherein there are speed-up means for automatically increasing the angular velocity of the co-rotatable sweeper-bar and waring implement whenever the indicator means indicates higher relative success for the operator's weapon.

7. The amusement apparatus of claim 4 wherein there are intermittent interrupter means for the robot program to render the apparatus adaptable for operators of relatively low weaponry skill.

8. The amusement apparatus of claim 1 wherein the target means includes a plurality of individual targets at distinctly separated locations, individual target members being briefly automatically displayed to the operator at ready-condition according to a prescribed target scheduling means; wherein the robot includes a simulated waring implement extendable directionally toward a plurality of said individual targets; wherein the robot programming means is capable of scoreable negotiation whenever the waring implement simulated competitive-armament is directionally extended toward a ready-condition target; and wherein for a given individual target member at ready-condition and upon its initial scoreable negotiation by the competing operator's weapon and the programmed competitive-armament there are means for automatically removing said scored target from ready-condition display.

9. The amusement apparatus of claim 8 wherein the individual targets are briefly displayed through its own electromagnet means, the targets display scheduling means comprising a stepper unit that is advanced step-

wise to the electromagnetic target display whenever a ready-condition target has been scoreably negotiated; wherein the robot waring implement is rotated through an electric motor; wherein the motor and waring implement reverse angular direction whenever the robot competitive-armament wins a target; and wherein there are motor speed-up means for automatically increasing the angular velocity of the co-rotatable sweeper-bar and waring implement whenever the indicator means indicates higher relative successes for the operator's weapon.

10. Amusement Apparatus of the shooting gallery type and comprising:

- A. An upright hollow housing having a rearward side including a light-transmissive panel whereby an operator positioned at an operator's station located rearwardly of the light-transmissive panel might peer into the housing interior toward the forward side thereof;
- B. Target means comprising a plurality of individual targets at distinctly separate locations within the housing, said individual targets being briefly automatically displayed to the operator at ready-condition according to a prescribed scheduling means;
- C. An operator's weapon attached to the housing and being manipulatable by the operator rearwardly of said light-transmissive panel, said operator's weapon being capable of apparently scoreably negotiating respective individual targets when manually aimed theretoward;
- D. A robot including simulated competitive-armament located within the housing between the light-transmissive panel and the said individual targets, said competitive-armament being viewable to the operator without obscuring attempts to aim the operator's weapon toward individual targets, said competitive-armament being directionally movable so as to be extendable toward respective individual targets and also being capable of apparently scoreably negotiating said target means;
- E. Program means for automatically controlling the time required for the competitive-armament to scoreably negotiate the individual targets; and
- F. Indicator means to indicate the relative success of the operator manipulated weapon and the automatically programmed competitive-armament to scoreably negotiate the target means.

11. The amusement apparatus of claim 10 wherein there are handicap means to adopt the apparatus to operators of widely differing weaponry skills.

12. The amusement apparatus of claim 11 wherein the robot competitive-armament is a simulated waring implement rotated through the shaft of an electric motor; and wherein the handicap means includes means for automatically reversing the angular direction of the co-rotatable motor shaft and waring implement according to the demonstrated relative competitive success of the operator's weapon and the competitive-armament thereby frustrating the operator's attempt to anticipate the robot.
